UNITED STATES PATENT OFFICE.

FRANK W. WOOD, OF MONTCLAIR, NEW JERSEY, ASSIGNOR TO CHAS. CORY & SON, INCORPORATED, OF NEW YORK, N. Y., A CORPORATION OF NEW YORK.

MULTIPLE-SOCKET RECEPTACLE STRIP.

Application filed December 23, 1919. Serial No. 346,894.

To all whom it may concern:

Be it known that I, FRANK W. Wood, a citizen of the United States, and resident of Montclair, in the county of Essex and State of New Jersey, have invented certain new and useful Improvements in Multiple-Socket Receptacle Strips, of which the following is a specification.

My invention relates in general to electrical switches, and especially to a multiple socket receptacle strip employed for detachably connecting extension circuits to a main circuit. Strips of this nature are generally employed where a temporary lighting system of some extent is desired, as in building operations, and they have been found especially useful in connection with shipbuilding. Consequently, it is necessary that they be both strong in construction and arranged to afford complete protection to the conductors under severe service conditions where they may be exposed to the weather, to chance blows and to constant danger of shortcircuiting from exposed metal parts of the structure being erected.

Such strips, as commonly used in connection with shipbuilding, include a pair of parallel rods or bus bars insulated and held in position by clamping them between blocks, usually of wood grooved to accommodate the bars, extending on opposite sides of the bars substantially throughout their length, the blocks being fastened together as by screws to hold the bars in place. The bus bars are spaced apart approximately the same distance as the split terminals of standard switch plugs; and by boring spaced pairs of adjacent holes through one of the insulating blocks and partly or entirely through the bus bars, a series of plug sockets is produced in which split terminal plugs may be detachably seated to connect extension circuits at will. These strips have ordinarily been made up by the workmen when needed; but this is of course undesirable because of the time required and the imperfections in the strips when so made. Even when manufactured under the best conditions, multiple socket strips constructed in this general way are open to several serious objections. For one thing, considerable time and labor is required in producing a thoroughly effective and safe strip, as the bars must be fitted in place with considerable care. If the bars

thus rendering the sockets useless; while if the grooves in which the bars are seated are too small the blocks will not meet and are likely to split if drawn together too tightly. Furthermore, when the blocks do not meet, a space is formed between the bus bars in which moisture may collect, incurring the risk of a short-circuit. Consequently, the bars must fit accurately in the strip grooves, necessitating a considerable expense for labor in the production thereof. Another objection, when the blocks are made of wood as is customary, is the tendency of the wood to warp. When this occurs, a space is practically always certain to be open between the bus bars in which moisture may collect, with resultant danger from a short-circuit. These considerations are particularly important when the strips are to be used in exposed places where they may be subjected to the direct action of mist and rain, the present strips being unsuited for use in many such places.

A further difficulty with this type of strip is the manipulation of the connection between the bus bars and the main circuit wires. This connection is ordinarily made at one end of the strip, for the sake of convenience; and the actual points of connection, if immediately adjacent the end of the protecting blocks, are so exposed that great care must be exercised to prevent the contact of a metal conductor with both points simultaneously. On the other hand, if the points of connection are spaced inwardly from the end of the blocks to permit the latter to protect said points, considerable inconvenience is entailed in making and breaking the connections, as they are not accessible from the outside of the strip without unscrewing the blocks.

The object of my invention is to produce a strip adapted to be used in exposed places which will be reliable under the most severe service conditions, more durable than the present two-block type, and which provides complete insulation for the bus bars and connections at all times. I accomplish this object primarily by molding the strip in unitary form. My invention in particular includes an arrangement of parts permitting the quick, cheap and easy manufacture of the strip in this way, eliminating the largest part of labor cost in manufacturing the strips and insuring complete insulation.

of the bus bars from each other at all times. For this purpose I have provided a construction which permits the bus bars to be suitably shaped up, as by drilling and tapping, prior to molding, the various recesses in the bars being so formed and arranged that they may be kept free during molding from the plastic insulating material by parts of the mold itself without interfering with the direct removal of the formed strip from the mold. Furthermore, in the preferred form of my invention, no manipulation of mold parts whatever is necessary in removing the formed strip except the usual separation of the halves of the mold.

In actual service it is desirable to place these strips in various out-of-the-way places, the position of the strip depending upon local conditions. Consequently the strip should be so constructed that it can either be laid flat with its sockets uppermost, or hung up by one end. To accomplish this object, it is necessary to provide one end of the strip with suspending means, ordinarily made of wire and preferably in the form of a hook, whereby the strip may be hung from a wire, rod, nail or other elevated support. It will be apparent that the metal suspending element must engage the strip firmly enough to sustain considerable weight where several plugs with depending wires are in the sockets, and at the same time must be thoroughly and carefully insulated from the bus bars. I have provided a construction in which a metal supporting element may either be molded in the strip or the strip may be so formed that the supporting element may be inserted therein when needed, the construction being such that the supporting element is completely insulated from the conductors. Furthermore, when the supporting element is in place, the strip may be placed in horizontal position upon a support without difficulty.

I have also provided means for readily connecting and disconnecting the main circuit wires and the ends of the bus bars adjacent said supporting element, said connection being operable directly without disturbing the strip and at the same time being spaced from the end of the strip to insure perfect insulation. Furthermore, I have provided a channel from which the main circuit wires may be led laterally from the connecting points without projecting beyond the end of the strip adjacent the supporting element. This is especially useful where said element is to be hung over a rod, pipe or similar rigid metal support, as a chance upward blow on the strip would force the upper end thereof strongly against said support, and would be very likely to force said support against the main circuit wires and produce a short-circuit. This,

of course, would be avoided by having such connections at the opposite end of the strip; but it is desirable to locate them adjacent the supporting element, as the main circuit wires may then be run along said support, which is ordinarily at some distance from the floor, keeping said wires out of the way of the passers-by. It will be noted that both ends of the bus bars are insulated, one end being completely enclosed, the other protected by the extension of the insulation far enough beyond its end to prevent simultaneous contact with both bus bars by accident.

It will also be apparent that my specific construction is peculiarly adapted for rapid and efficient molding; and a substantial part of my invention involves the production of such a construction and the employment of standard and simple features in such a way that the whole may be rapidly molded.

Other objects and advantages of my invention will be apparent from the following description taken in connection with the accompanying drawings, in which:

Fig. 1 is a top plan view of the strip,

Fig. 2 is a longitudinal section through one of the bus bars, showing the plug in elevation engaging one of the sockets,

Fig. 3 is a transverse section through a form of plug which may be employed, and

Fig. 4 is a transverse section on line 4-4 of Fig. 1.

The strip includes one or more bus bars 11, of any desired form, extending substantially throughout the length of the strip. Bus bars 11 are parallel and spaced apart, their centers being preferably spaced by a distance equal to that between the split terminals of standard plugs. The bus bars 11 are imbedded in a homogeneous, integral casing strip 12, formed of any suitable non-conducting material adapted to be molded, various materials of this kind being well known in the art and in common use for making electrical devices. A series of spaced pairs of adjacent socket holes 13 extend from one surface of the strip through the casing material 12 and bus bars 11, each pair of socket holes 13 defining sockets for the reception of the terminals of a plug, the holes being so located in the bus bars that sufficient metal is left adjacent the holes to provide a suitable conductor for the current past the holes.

As shown, the casing 12 extends completely across the lower end of each bus bar 11, providing complete insulation for said end. The opposite end of each bus bar 11 terminates short of the end of the casing 12, which is provided with a recess or channel 14 extending outwardly from said end of the bus bar to the outside of said casing. Said recess or channel 14 may be varied in

shape, being adapted to accommodate the end of a main circuit wire 15 held in contact with the bus bar. For maintaining this connection, I preferably provide a terminal socket 16 in the end of each bus bar 11, into which the end of the lead wire may be inserted, where it is held in any desired way, as by a set screw 17 threaded through a tapped opening in the side of the bus bar 11 at the socket 16 and manipulated through a lateral opening or well 18 in the casing 12. It will be noted that the parts are preferably so proportioned that the head of each screw 17 is a considerable distance below the surface of the casing 12, preventing chance contact with the adjacent terminal screw. It will also be apparent that, while the insulation of the lead wire 15 must necessarily be stripped from the end thereof to permit proper contact with the bus bar, channel or recess 14 is of sufficient depth so that wire 15, on emerging therefrom, is properly protected by its normal insulation, channel or recess 14 being sufficiently large to accommodate the raw end of the insulating material.

I have also disclosed a suitable supporting member 19 mounted on the strip adjacent the bus bar terminals. In the form illustrated, this is composed of a wire having a hooked upper end 20, and a hooked lower end 21 passing through and engaging the strip, the intermediate part of the wire being imbedded in the surface of the strip and preferably lying flush therewith, the lower end of the wire being given a return bend 22 flush with the surface of the strip, if desired. It will be evident that with this construction, the strip may either be laid flat upon the side opposite the socket openings 13 or it may be suspended by hook 20, which may be shaped in any preferred way according to the nature of the supports which will be engaged thereby.

In the specific construction disclosed, it will readily be understood that supporting means 19 may either be fixed in position during molding, or a suitable socket therefor may be provided during molding and the support placed therein when and if needed. When the latter method is employed, the strip is preferably formed with suitably shaped depressions during molding, the form illustrated including a pair of opposite grooves 23 connected by a transverse bore 24, the construction being such that a wire may readily be passed through the bore 24 and its ends bent up to form the return bend 22 and hook 20, the intermediate parts of the wire lying flush with or below the surface of the strip.

The simplicity and effectiveness of the construction and arrangement of parts as described will be apparent; but one of its main advantages lies in the facility with

which it may be rapidly and effectively molded, this condition requiring a carefully planned arrangement not necessary when the strip is produced in other ways.

Furthermore, all of the shaping operations on the bus bars, which in the specific form shown include drilling and tapping, may be performed prior to the molding process. This is highly desirable, as any such operations performed after molding would be likely to loosen the bars in the casing. However, careful provision must be made for preventing the entry of the plastic covering or insulating material into the various sockets or depressions, and it is highly desirable that such preventing means be mounted rigidly within the mold so that little or no manipulation is required before removing the strip, the arrangement preferably being such that an ordinary two-part mold may be used.

It will be evident that the construction disclosed meets all of these requirements, as the bus bars may be positioned in the mold upon pins projecting from the bottom thereof, a similar pin resting against the tapped hole through which screw 17 passes. The channels 14 may be produced by plugs projecting inwardly from the end of the mold and slideable outwardly therethrough after molding to permit the withdrawal of the strip, the form of plugs used being determined by the form of channel 14 desired. This, however, would require a slight manipulation of the mold; and while it falls within the scope of my invention, I have disclosed a construction in which channels 14 extend downwardly to the bottom of the mold, and may be formed by suitable rigid flanges. It will be apparent that with this specific construction the placing of the bus bars in the mold upon the proper pins and flanges will both close the apertures in the bus bars and at the same time provide suitable recesses in the mold casing; while after molding the strip may be removed directly from the mold without difficulty. The mold construction for molding channels 23 and bore 24, or for molding with support 19 in place, is obvious.

I have disclosed in Fig. 3 a suitably formed plug adapted to be used in connection with my multiple socket receptacle, said plug including a two part body 26 of insulating material, the halves of which are detachably connected, as by bolts 27. Suitably positioned between the halves of body 26 are conducting rods 28, provided with split terminals 29 projecting beyond the body 26, and at their opposite ends having suitable terminal sockets 30 adapted to hold the ends of the auxiliary circuit wires 31 in any desired way, as by set screws 32. If desired, one of the conductor rods 28 may be made in two parts connected by a fuse 33.

frictionally engaging sockets in the ends of said parts. The plug may further be provided with a suitable looped supporting element 34.

5 It will be apparent that I have devised a multiple socket receptacle strip which combines the three primary requisites of strength and durability, thorough and lasting protection against short-circuits, and 10 cheapness of production. The strip is, furthermore, adapted to be used in a great variety of locations and under differing conditions, being resistant to varying conditions of temperature and humidity, and to the 15 roughest usage, without losing its effectiveness. Its rigidity and arrangement permit its use in a flat, a hanging or a leaning position, and the connections both with the auxiliary circuit plugs and with the main 20 circuit leads can be readily and rapidly made. Furthermore, the strip is practically a one-piece construction, eliminating the danger of losing parts.

While I have described the preferred 25 form of my invention, it will be apparent that certain changes may be made in the details thereof without departing from the spirit of my invention as set forth in this specification.

30 I claim:

1. A multiple socket receptacle strip including a plurality of parallel bus bars having relatively spaced sockets therein, an integral casing of insulating material molded around the bus bars and completely enveloping the same at one end, the said casing having socket holes in one side face extending inwardly into registration with the respective bus bar sockets, the bus bars being 35 terminated short of both casing ends, the casing being provided at the end opposite to that at which the bus bar ends are completely enveloped with lateral recesses contoured for the reception of the main or 40 feed wires, the said recesses extending from the adjacent bus bar ends to the face in which the socket holes are located, the casing having lateral openings extending from the said bus bar ends to the said face of the 45 casing and terminal connectors for the last mentioned ends of the bus bars contained within the lateral openings of the casing.

2. A multiple socket receptacle strip including a plurality of parallel bus bars having relatively spaced sockets therein, an integral casing of insulating material molded around the bus bars and completely enveloping the same at one end, the said casing having socket holes in one side face extending 55 60 inwardly into registration with the respec-

tive bus bar sockets, the bus bars being terminated short of both casing ends, the casing being provided at the end opposite to that at which the bus bar ends are completely enveloped with lateral recesses extending from the adjacent bus bar ends to the face in which the socket holes are located, the last mentioned bus bar ends being provided with terminal sockets and lateral threaded openings in communication therewith, the casing having lateral openings extending from the said bus bar openings to the face through which the recesses open, and terminal connecting screws engaged within the said bus bar openings and being contained within the lateral openings of the casing.

3. A multiple socket receptacle strip including a plurality of parallel bus bars having relatively spaced sockets therein, an integral casing of insulating material molded around the bus bars and completely enveloping the same at one end, the said casing having socket holes in one side face extending inwardly into registration with the respective bus bar sockets, the bus bars being terminated short of both casing ends, the casing being provided at the end opposite to that at which the bus bar ends are completely enveloped with lateral recesses open at the said end of the casing and extending across the adjacent bus bar ends to the face in which the socket holes are located, and terminal connectors provided at the last mentioned ends of the bus bars.

4. A multiple socket receptacle strip including a plurality of parallel bus bars having lateral sockets, an integral casing of insulating material molded around the bus bars and having socket holes extending inwardly from one side face into registration with the respective bus bar sockets, and terminal connectors for the bus bars embedded within the casing, the said casing being provided near one end with a transverse opening located midway between bus bars and spaced therefrom and with longitudinal grooves in its external faces in registration with the said opening and extending through the said end of the casing, and a wire suspending element extending through the casing opening and bent to fit the said grooves, part of the said element being extended beyond the adjacent end of the casing.

Signed at New York in the county of New York and State of New York this 20th day of December A. D. 1919.

FRANK W. WOOD.
